DESIGN FOR AN ENVELOPE MOISTENER

Aaron H. Lippman, Jamestown, N. Y., assignor
to Jay-Lip Corporation, Jamestown, N. Y., a
corporation of New York

Application May 31, 1946, Serial No. 130,275

Term of patent 14 years

(Cl. D74—10)

To all whom it may concern:

Be it known that I, Aaron H. Lippman, a citizen of the United States, residing at Jamestown, in the county of Chautauqua and State of New York, have invented a new, original, and ornamental Design for an Envelope Moistener, of which the following is a specification, reference being had to the accompanying drawing, forming part thereof, and in which

Fig. 1 is a side elevational view of an envelope moistener, showing my new design;

Fig. 2 is a front elevational view thereof; and

Fig. 3 is a top plan view of the same looking in the direction of the arrows 3—3 on Fig. 2.

I claim:

The ornamental design for an envelope moistener, substantially as shown.

AARON H. LIPPMAN.
